CLAIM

The ornamental design for a selfie stick, as shown and described.

DESCRIPTION

FIG. 1 is a front elevational view of a selfie stick showing my new design in a handheld status;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a rear, left and top perspective view thereof;

FIG. 8 is a front, right and bottom perspective view thereof;

FIG. 9 is a rear, right and top perspective view thereof;

FIG. 10 is a rear, left and top perspective view thereof;

FIG. 11 is a front elevational view of the selfie stick in a folded status;

FIG. 12 is a rear elevational view of FIG. 11;

FIG. 13 is a left side view of FIG. 11;

FIG. 14 is a right side view of FIG. 11;

FIG. 15 is a top plan view of FIG. 11;

FIG. 16 is a bottom plan view of FIG. 11;

FIG. 17 is a front, left and bottom perspective view of FIG. 11;

FIG. 18 is a front, right and bottom perspective view of FIG. 11;

FIG. 19 is a rear, left and top perspective view of FIG. 11;

FIG. 20 is a front, right and top perspective view of FIG. 11;

FIG. 21 is a front elevational view of the selfie stick in a standing status;

FIG. 22 is a rear elevational view of FIG. 21;

FIG. 23 is a left side view of FIG. 21;

FIG. 24 is a right side view of FIG. 21;

FIG. 25 is a top plan view of FIG. 21;

FIG. 26 is a bottom plan view of FIG. 21;

FIG. 27 is a front, left and top perspective view of FIG. 21;

FIG. 28 is a front, right and bottom perspective view of FIG. 21;

FIG. 29 is a rear, left and bottom perspective view of FIG. 21; and,

FIG. 30 is a rear, right and bottom perspective view of FIG. 21.
